DITCHING AND LOADING DEVICE

Archie Radakovich, Kelso, Wash.

Application March 16, 1948, Serial No. 15,197

3 Claims. (Cl. 198—11)

1

This invention relates to ditching and loading machines and is particularly adapted to be used in the digging of ditches along roadways and the loading of gravel and the like from stock piles into trucks.

The primary object of the invention is to mount a conveyor on wheeled supports at one of its ends and having a digger shovel associated with its opposite or lower end.

A further object of the invention is to provide a power unit mounted to the said wheels for driving the machine over the surface of the ground, and also supplying power for operating the conveyor and the digging shovel.

A still further object of the invention is to provide a pivotally mounted horizontal delivery conveyor for receiving materials delivered by the first said conveyor, delivering them to a desired destination relative to the machine.

A further object of the invention is to provide adjustable supporting means for raising and lowering the digging shovel.

A still further object of the invention is the mounting of the primary conveyor off center relative to the supporting wheels so that the machine can be attached to a truck, grader or other implement used in construction work. This permits the conveyor to operate along side of the said machine and still having its supporting and driving means tracking along behind the machine.

And a further object of the invention is to provide a digging and loading machine that can be operated independently from other implements, making it possible to use the same for loading gravel from stock piles into trucks, or even digging excavations and loading the material on said trucks.

In the operation of my new and improved digging and loading machine where the same is being used to dig ditches parallel to highways, I find that the best method of operation is to connect it to a truck or grader working in combination with the same. This provides for greater strength and rigidity in the operation of the machine offering better control of the shovel in the digging operations, also in the case of a truck it provides a place for loading the excavated materials.

These and other incidental objects will be apparent in the drawings, specification and claims.

Referring to the drawings:

Figure 1 is a side elevation of my new and improved digger and loading machine, the broken

2

lines indicating the relative position of a truck or grader.

Figure 2 is a fragmentary detail view illustrating a rotary cutting blade associated with the digging shovel.

Figure 3 is a front view of Figure 2 looking in the direction indicated.

Figure 4 is a rear view taken on line 4—4 of Figure 1, showing the method of mounting the conveyors and associated parts upon the supporting wheels.

Figure 5 is a sectional plan view taken on line 5—5 of Figure 4.

Figure 6 is a plan view of the machine as the same would appear mounted to a truck, parts broken away for convenience of illustration.

Figure 7 is a plan view of Figure 1.

Figure 8 is a fragmentary detail of my new and improved digging machine adapted to a standard grader blade, the grader supporting the forward end of the conveyor and the shovel controlling the same in the operation of digging the ditch.

Referring more specifically to the drawings:

25 My new and improved digging and loading device consists of a primary elevating conveyor 1. Located on the lower end 2 of the conveyor is a digging shovel 3 consisting of a blade 4. The side walls 5 of the shovel form part of the 30 side rails 6 of the conveyor. The opposite and upper end 7 of the conveyor is mounted upon the axle 8 of the wheels 9 by way of the supporting vertical frame 10, which is secured to the underside of the conveyor 1 at 11 at its 35 upper end and having its lower end fixedly secured to the axle housing 12.

A horizontal A-frame 13 is fixedly secured to the vertical frame 10 at 14 and to the underside of the conveyor 1 at 15. This makes a solid and rigid connection between the axle housing 12 of the wheels 9 and the conveyor 1. The shovel 3 is carried by the wheel assembly 16 consisting of the wheel 17 journaled to the lower end of the supporting fork 18, which in turn is pivotally mounted to the conveyor 1 at 19.

40 45 The shovel 3 is raised and lowered by adjusting the angle of the fork 18 through the adjusting bolt 20, which is pivotally mounted to the arm 18 at 21 at its one end and anchored to the bracket arm 22 through the adjusting nuts 23 at its upper end. The supporting wheel assembly 16 is not always used in connection with my machine, as there are applications of the same to graders and the like where the auxiliary machine would support the shovel 3.

The conveyor 1 consists of the side rails 6 and a partial bottom 24 and has the conveyor belt 25 trained about the idler roller 26 at its lower end and the driving roller 27 at its upper end adjustably mounted by suitable tightening means 28 to the conveyor and driven by the drive chains 29 and 30. The chain 30 is driven directly from the shaft 31 of the transmission 32 of the motor 33.

In some operations I include a digging rotor 34 which is rotatably mounted to the swinging arms 35, which are pivotally mounted to the cross shaft 36, which is journalled within bearings 37 forming part of the shovel side walls 5. The rotor 34 is driven by the driving chains 38, 39 and 40, the latter chain extending longitudinally of the conveyor 1 to be driven in any convenient manner, as by the shaft 30 which couples the chains 29 and 30. A secondary conveyor 41 is mounted to the vertical pedestal 42, best illustrated in Figures 1 and 4.

The vertical pedestal 42 consists of a gear box 43 fixedly mounted to the cross frame or platform 44, which in turn is mounted to the axle housing 12 through the brackets 45. The conveyor 41 is pivotally mounted at 46 to the upper ends of the supporting arms 47, the lower ends of said arms being fixedly mounted at 48 to the gear housing 49. The gear housing 49 is rotatably mounted at 50 to the upper end of the gear housing 43. The conveyor is further supported by the telescopic bar assembly 51, which is pivotally mounted at 52 to the pedestal 42 and at 53 to the underside of the conveyor 41.

The conveyor 41 is held at any desired lateral angle to the conveyor 1 by the locking or unlocking of the hand wheel 50. The hand wheel 50 forms part of a set screw threaded within the collar 50 forming part of the housing 42, the end of the set screw engaging the lower portion of the housing 49 to retain the latter in selected angular position.

I will now describe the method of driving the conveyor belt 54 of the conveyor 41. The shaft 31 drives through the transmission 55 into the gear box 43 through the gear box 56 through the housing 49 by way of the drive shaft 57 which drives the chain 58 and the belt roller 59. The conveyor 41 may be adjusted to any angle to the conveyor relative to the longitudinal line of the machine, as one of the primary objects of my invention is to be able to deliver the material from the primary conveyor in any horizontal direction relative to the machine. I have not attempted to illustrate the gearing within the housings 43 and 56 because this is of a well known type of power transmission.

I will now describe the method of propelling the machine over the ground surface. A chain 60 drives the transmission 61, which in turn drives the wheels 9 by means of the chain 63 and sprocket 62 which is drivingly connected through a typical differential 60' with the wheel axle 8. The wheels 9 are mounted to the axle 8 by the well known ball and socket connections 64, and in order to steer the machine a tie-rod 65 is pivotally connected to the wheel assemblies at 66.

A reduction gear box 67 is fixedly secured to the platform 44 at 68 and has a crank arm 69 extending therefrom cooperating with the rollers 70, which are spaced apart and journalled to the tie-rod 65. When the crank is turned by the downwardly extending stub shaft 71 through the gear reduction located in the housing 67,

which in turn is operated by the hand crank 72, the wheels will be turned about their ball and socket connections 64 steering the machine over the ground surface. I do not wish to be limited to the particular form of driving units described and shown in my drawings, as all of the elements may be controlled with well known drives, as for instance the whole machine could be operated by hydraulic motors from a central hydraulic pump.

Referring to Figure 6, I illustrate my digger and loader adapted or mounted to a truck. A universal connection 73 is secured to the frame 10 of my machine at 74 and to the truck 75 at 76. The forward end of the conveyor 1 and shovel 3 are connected to the forward end of the truck by a well known system, consisting of a bar 77 pivotally mounted to the truck at 79 and to the shovel 3 at 80 and a hydraulic cylinder 81 connected to the bar 77 at 78 and to the shovel 3 at 82. This bar assembly is telescopic so that the operating cylinder 81 may move the shovel 3 away from or toward the truck while digging the ditch D.

In Figure 6 it will be noted that the wheels 9 are parallel to the longitudinal center line of the truck, while the conveyor is at an angle to the truck while digging the ditch. This adjustment is made by the above described steering apparatus controlled from the steering handles 72.

It will be noted that the structure of my machine is such that the delivery end of the conveyor is of sufficient height to clear the wheels of the truck 75 and to elevate the materials sufficiently high to deliver the same into the truck body by the secondary conveyor 41. The conveyor 41 is shown in Fig. 6 in position for delivering to the truck, but it may be turned to any desired angle relative to the primary conveyor 1, as for instance cross wise of the ditch to the outer bank of the ditch.

Referring to Figure 8, I illustrate a fragmentary portion of my machine adapted to the blade 83 of a grader by suitable toggle linkage 84. The raising and lowering mechanism of the grader will be employed to raise and lower the digger shovel 3 in the work being performed, usually ditching and so forth. When my invention is being used as a loading device it is usually used separately, as for instance when loading gravel off of gravel piles into trucks, or if it is being used for excavating purposes, it may also be used as a separate machine, but when the same is being used in connection with other implements it is easily and quickly attached by special fittings as above described.

What I claim, as new, is:

1. A conveying machine comprising, in combination, a pair of wheels mounted to an axle, a frame mounted on said axle and pivotal thereon, a chute rigidly mounted on said frame at an angle forwardly of said wheels with its lower forward end at ground level, said chute being at an angle to the path of said wheels to position its forward end laterally of the wheel path, a third wheel supporting the forward end of said chute, a blade on the forward end of said chute for scooping up loose material, a continuous conveying means in said chute for moving the material the length of said chute and discharging it at the other end thereof, a second chute pivotally supported adjacent one end by said frame, said second chute being pivotal about a vertical axis located beneath the upper discharge end of said inclined chute,

so that one end of said second chute is under said discharge end to receive the discharged material regardless of the angle of said second chute, a continuous conveying means in said second chute for moving the material to and discharging it from the opposite end thereof, and drive means carried by said frame for driving both of said conveying means and said wheels.

2. A machine as defined in claim 1, including a vertical housing carried by said frame, a transverse housing pivotally mounted on the upper end of said vertical housing and forming a yoke, a shaft journalled in said transverse housing and extending beyond one end thereof, a transmission between said shaft and said drive means and extending through said vertical housing to drive said shaft, a second shaft journalled in said yoke, a drive between said shafts, said second chute being journalled on said second shaft within said yoke, an adjustable brace between said chute and said vertical housing and an endless conveyor within said second chute and trained around said second shaft to be driven thereby.

3. A machine as defined in claim 1, wherein said drive means comprises a power unit including a transmission to said conveying means, a steering means is connected to said wheels, and a manually controlled transmission from said power unit is connected to said wheels whereby said machine is self-propelled.

ARCHIE RADAKOVICH.
